UNITED STATES PATENT OFFICE.

SAUL GELARIE, OF BROOKLYN, NEW YORK.

REINFORCED BLOOMERS.

Application filed February 16, 1921. Serial No. 445,424.

To all whom it may concern:

Be it known that I, SAUL GELARIE, a citizen of the United States, and a resident of the city of New York, borough of Brooklyn, 5 in the county of Kings and State of New York, have invented new and Improved Reinforced Bloomers, of which the following is a full, clear, and exact description.

The invention relates to wearing apparel 10 and its object is to provide new and improved reenforced bloomers or pantalets arranged to render the legs exceedingly strong and durable to withstand strains and wear incident to the user riding horseback or 15 otherwise exercising and spreading the legs when climbing hills or during country running or indulging in other athletic sports.

Another object is to provide the desired fullness particularly at the seat to allow the 20 user to sit down comfortably on a saddle, chair or other support.

With these and other objects in view, the invention consists of certain novel features of construction, as hereinafter shown and 25 described and then specifically pointed out in the claims.

A practical embodiment of the invention is represented in the accompanying drawings forming a part of this specification, in 30 which similar characters of reference indicate corresponding parts in all the views.

Figure 1 is a front perspective view of the bloomers;

Figure 2 is a rear perspective view of the 35 same;

Figure 3 is an enlarged sectional plan view of a portion of the same on the line 3—3 of Figure 1; and

Figure 4 is a plan view of the reinforcing 40 pieces.

The reenforced bloomers comprise in general construction a body 10 and legs 11, of which the body 10 is provided at the waist with a hem 12 containing an elastic band 13 for tightly holding the bloomers in position on the waist of the wearer. The lower ends of the legs 11 are provided with hems 14 containing elastic bands 15 for snugly fitting the bottoms of the legs 11 in position on the wearer's legs. In practice, the body 10 and legs 11 are made of two pieces of knitted or woven textile material fastened together by stitches to provide front and rear main trunk seams 20 and 21 extending 55 along the front and rear median lines of the body and joining at the crotch, and the

two pieces are fastened together by stitches to form main leg seams 22 extending along the inner sides of the legs 11 and intersecting the seams 20 and 21 at the crotch. 60

The bloomers are reenforced by two front pieces 25 and two rear pieces 26 (shown in Figure 4), and joined at their inner edges 27 and 28 with the seams 22 and fastened at their outer edges by stitches 29 and 30 to the body 10 and legs 11, as plainly indicated in Figures 1, 2 and 3. The lower ends of the reinforcing pieces 25 and 26 are joined with the hems 14 of the legs 11. By reference to the drawings it will be noticed that the reinforcing pieces 25 and 26 gradually increase in width from the bottoms of the legs 11 to the upper ends thereof, and the upper ends are curved inwardly towards each other to join with the front and rear 75 seams 20 and 21. It will further be noticed that the front reinforcing pieces 25 are somewhat narrower than the rear reinforcing pieces 26 for the purpose of providing the desired fullness at the seat of the 80 bloomers to enable the user to comfortably sit down on a saddle, chair or other support. It will further be noticed that by reinforcing the bloomers throughout the entire length of the legs at the inner portions thereof the legs are capable of withstanding undue strain and wear incident to the user riding horseback or otherwise exercising or spreading the legs when climbing hills or when running or indulging in other athletic 85 sports.

In practice the reinforcing pieces 25 and 26 are of the same material as that of which the body 10 and the legs 11 are made.

Having thus described my invention, I 90 claim as new and desire to secure by Letters Patent:

1. Reenforced bloomers or pantalets, comprising a body, legs and reinforcing front and back pieces overlying portions of the 100 body and legs, the body having front and rear seams coinciding with the front and rear median lines and joined at the crotch, and the legs having seams at the inner sides joining the said front and rear seams at the 105 crotch, the said reinforcing pieces being joined at their inner edges with the said seams, and stitches fastening the outer edges of the said reinforcing pieces to the said legs and body. 110

2. A bloomer garment having front and rear parts that are united by a central seam

- that extends down the front, through the crotch and up at the rear thereof and also having an inseam that extends continuously up one leg, across the crotch and down the 6 other leg and separate strips of material secured to the garment and each strip having an edge that is included in the said central seam and each strip having another edge that is included in the inseam.
- 10 3. A bloomer garment having front and rear parts that are permanently stitched together through the crotch and each part having a separate strip secured thereto and said parts and strips all having an edge that 15 forms a part of a central seam through the crotch and another edge that is included in and forms a part of an inseam that crosses the crotch of the garment.
4. A bloomer garment having two front 20 parts and two rear parts which are permanently stitched together through the crotch and each of the four parts having a separate strip of material secured thereto, the four strips and the four garment parts 25 being united by a central seam from front to rear across the crotch and the four strips and four garment parts being united by an inseam from side to side across the crotch,—
- said garment being permanently closed at the front and rear through the crotch. 30
5. A bifurcated garment having a gusset set therein reaching from the crotch to the leg ends of the garment, said gusset having the central portion thereof anchored with the main leg and trunk seams of the garment. 35
6. A bifurcated garment having a gusset of a relatively tapering outline reaching from the crotch to the leg ends of the garment, said gusset having the outline stitched 40 to the garment and the central portions secured and anchored in the main seams of the garment adjacent thereto. 45
7. A bifurcated garment having a gusset associated therewith, which is made up of 50 separate correlated pieces and positioned and secured to the garment to cover the areas of the legs thereof between the crotch and the leg openings on either side of the inner and main leg seams, the latter seams anchoring said gusset pieces on the central parts thereof for making a unit gusset of said separate pieces and for reinforcing the garment.

SAUL GELARIE.
